UNITED STATES PATENT OFFICE

GIOVANNI B. SCARAMUZZA, OF LA CEIBA, HONDURAS, CENTRAL AMERICA

EXTENSION LADDER

Application filed August 26, 1927. Serial No. 215,736.

The object of this invention is to provide a device which may be used in complete form as a single ladder, but comprising two main elements which may be detached, and employed as separate ladders,—and further to provide a device which may be used as an extension ladder or as a scaffold supporting device, adapted for service when resting upon an uneven base or upon the ground, where portions of the surface thereof lie at different elevations.

A further object is to provide particular retaining means for holding the main sections of the ladder in position for the particular use to which the device is to be applied at a given time.

In the drawings forming part of this application,

Figure 1 is a view of the complete device, in elevation.

Figure 2 is a view in elevation, from the opposite side.

Figure 3 is a view in edge elevation.

Figure 4 is a view in vertical section.

Figure 5 is a transverse section on line 5—5 of Figure 1.

Figure 6 is a section on line 6—6 of Figure 1.

Figure 7 is a section on line 7—7 of Figure 1.

Figure 8 is a fragmentary view in edge elevation, showing the relative position of the ladder sections when separated at the lower ends, so that the device may be used as a step ladder, or for supporting a scaffolding.

The device comprises a plurality of ladders, or ladder sections, designated 10 and 12, the stiles of the section 10 having longitudinal grooves on the inner surfaces thereof, these grooves terminating in cutaway portions near their lower ends. The grooves are designated 13 and the cutaway portions are shown at 14. The section 12 of the ladder, or the stiles thereof include brackets 15 having outwardly extending lugs 16 cooperating with the grooves, so that the stiles of section 12 will be retained in proper relation to the stiles of section 10, but these sections are relatively slidably, section 12 being of less width than the other section.

The transverse elements, rounds, or steps of the sections are designated 10' and 12' and these are adapted to lie opposite each other, to form a type of double step, when the sections are in the position of Figure 4, the ladder then not serving as an extension ladder, but the same relative position of the elements forming the steps, will hold good when sections 10 and 12 are extended, if portions of the sections still overlap.

Carried by section 10 of the ladder are brackets such as 18, providing bearings 19 for transverse rod or shaft 20, this shaft carrying an operating member, lever, or handle, 21, by means of which the shaft is rocked. Arms 22 or brackets 22 are rigid with shaft 20, and are offset as shown, so that the upper portion will lie above the upper surface of the round of section 10 of the ladder, and the outer portion of each arm or bracket will rest beneath the rounds of the section 12 of the ladder, thereby supporting the latter when extended. As the section 12 is moved upwardly, the rounds thereof, beginning with the third round or step from the top, will impart upward movement to the brackets carried by shaft 20, and will swing these brackets, and partly rotate the shaft, so that the brackets will be thrown clear of the rounds and permit longitudinal movement of the section 12, to the extent desired. These brackets on shaft 20 are sufficiently heavy to drop back to operative position, by gravity, so that reengagement is automatically produced, and it is only necessary to move the extension element to the position desired, and then proceed with the use of the ladder.

Brackets 25, are carried by the stiles of section 10, and these brackets include inwardly extending arms 28, aiding in the guiding movement of the slideable sections.

In using the device as a step ladder, or making any use thereof requiring the separation of the sections in V-form,—the section 12 is first elevated to a slight extent from its lower position, the recesses 14 being just above the lower ends of the grooves. When the lugs carried by section 12 are opposite the recesses in the stiles of the outer section, the section 12 of the ladder is swung outwardly at the

bottom. The upper step or round of section 12 should rest upon the brackets carried by shaft 20. Section 12 being swung outwardly, the notches 31 of plates 32 on section 12 engage the arms of brackets 25', these arms extending inwardly for the purpose indicated, and the main sections of the ladder are held in V-form.

Having described the invention what is
10 claimed is:—

In a device of the class described, a plurality of ladder sections including stiles and steps, means for guiding one section and affording parallel sliding and longitudinal movement thereof with reference to the other section, in producing an extension ladder, a transverse shaft mounted for rotation, on one of the ladder sections, brackets extending radially from the shaft and deflected downwardly between oppositely located steps of the ladder sections, these brackets being adapted to support the slideable ladder section when moved angularly with reference to the other section, said slideable section including notched portions, and devices carried by the stiles of the section mounting the shaft, and extending inwardly toward each other, acting as guiding devices, of angular form, extending around two sides of each stile of the other section during parallel movement between the sections, and adapted to enter the notched portions for pivotally supporting the slideable ladder section when moved angularly with reference to the other section.

35 In testimony whereof I affix my signature.
GIOVANNI B. SCARAMUZZA.
